UNITED STATES PATENT OFFICE.

LEVI P. WELLS, OF GERING, NEBRASKA.

COMBINED CLAMP AND WHEEL-GUARD FOR FARM-WAGONS.

1,353,940.

Specification of Letters Patent. Patented Sept. 28, 1920.

Application filed July 2, 1919. Serial No. 308,141.

To all whom it may concern:

Be it known that I, LEVI P. WELLS, a citizen of the United States, and a resident of Gering, in the county of Scotts Bluff and State of Nebraska, have invented certain new and useful Improvements in Combined Clamps and Wheel-Guards for Farm-Wagons, of which the following is a specification.

10 My invention relates generally to improvements in farm wagons, it relating more particularly to combined clamps for the wagon box sides and guards for the bottoms of such wagons, and it consists in the constructions, combinations and arrangements herein described and claimed.

The foremost object of my invention is to provide a device for keeping the front wheels of the farm wagon from wearing holes in the adjacent corners of the wagon box in making turns, this device being in the nature of a metallic guard to be applied to the place where the wear usually comes, it at the same time including a clamp for holding the upper board of the wagon box side down.

A further object of the invention is to provide a combined guard and clamp, both of which, while serving independent purposes, mutually coöperates as to practically constitute one appliance.

Other objects and advantages will appear in the following specification, reference being had to the accompanying drawing, in 5 which:—

Figure 1 is a side elevation of a farm wagon illustrating the application of the invention,

Fig. 2 is a detail cross section showing the combined guard and clamp in place,

Fig. 3 is a perspective view of the improved guard, and

Fig. 4 is a plan view of the metal blank, showing the lines on which the blank is bent to form the improved guard.

Before proceeding with the description of the invention, it is thought well to briefly describe the objections which the invention seeks to overcome. It is common knowledge that the front wheels of farm wagons wear holes in the adjacent edges of the wagon box. This wearing action takes place in making curves, at which times, one or the other of the front wheels engages the edge of the wagon box and grinds the wood away.

It has been sought to overcome this evil

by applying guards of various kinds, some of which are in the nature of iron pieces which extend across and are intended to intercept the edge or rim of the wheel on each side, so as to prevent the wearing of the wood. Some of the guards now in use are so heavy as to make their universal use prohibitive. Generally, the guards now in use are objectionable in one way or another, and it is to overcome all present objections, that I have produced the comparatively simple guard illustrated in the drawing.

A piece of metal 1 is bent into the shape of a wheel guard and is applied to the edge 70 of the wagon box 2 at the place where the wear of the front wheel 3^a comes, when a turn is made. Although the guard may be cast into the shape shown, it is preferably made of spring steel, or sheet metal of such 75 a nature that the guard will be of harder material than that of which the tire of the wheel 3 is made.

Referring to Fig. 4, it is to be observed that a substantially square piece 1 is employed. This piece is folded diagonally across along the line 2, then folded back upon itself along the line 3, then bent upwardly along the line 4 so as to produce the vertical side 5 of the guard, then folded outwardly along the line 6 so as to produce the horizontal clamp head 7, and finally is bent down along the line 8 so as to produce the retaining lips or lugs 9.

A notch 10 is cut in from the front point 90 of the sheet metal blank 1, that is to say, from the point which extends outwardly from the side of the wagon when the guard is applied. This notch receives the lower end of the clamp rod 11. This end is 95 threaded so as to receive the wing nut 12. The lips or lugs 9 prevent the wing nut from slipping out of position by the rattling and vibration of the wagon. The wing nut is prevented from unscrewing and dropping 100 off, by the insertion of a nail 13 in the hole 14 at one or the other side of the notch 10. The nail remains in place by gravity and by engaging one of the wings of the nut 12, keeps the nut from turning off of the 105 threaded end of the rod 11.

It is to be observed that the horizontal side of the guard, namely, that side which goes under the wagon box, is provided with preferably two apertures 15, through which 110 bolts or other securing means 16, pass to secure the guard. A single aperture 17 is

provided in the vertical side 5, and through this aperture, a bolt or similar fastening device 18 is passed to secure the front side of the guard.

5 The clamp rod 11 extends up the side of the wagon and is bent over at 19. This bent over portion or hook 19 holds the upper part of the side of the wagon box down. An eye bolt 20 secures the rod 11 to the upper flank, 10 as clearly shown in Fig. 2. There is a mutual coöperation between the clamp rod 11 and the guard. The clamp rod serves to hold the top flank of the wagon side down in place, but this function can be performed 15 only by means of connection of the clamp rod with the clamp head 7 of the guard. On the other hand, the connection between the clamp rod and the head of the guard, serves to support or hold the guard in place. Of course the fastening means 16, 18 primarily 20 do this, but should it ever happen that the bolt 18, for example, should become loose, it is easy to see that then the clamp rod operates to hold the guard up in place along 25 side of the wagon box, taking the place of the bolt which is now presumed to be loose.

One feature of importance that should have been stated above, is the provision of the double thickness of hard metal in the 30 guard where the wear occurs. The folds 2, 3 and 4 provide the inwardly directed resilient hardened flange 22, clearly shown in Fig. 2. The reader will observe at once that this double thickness of flange is gotten by 35 doubling or folding the metal upon itself in the manner stated, so that while the rest of the body of the guard is relatively thin, the flange 22 where the wear occurs, is thick enough for all practical purposes.

40 While the construction and arrangement of the combined guard and side board clamping device, is that of a generally preferred form, obviously modifications and changes may be made without departing from the 45 spirit of the invention or the scope of the claims.

I claim:—

1. Means for preventing the wearing of a

hole in a wagon box by the turning of a front wheel, comprising a guard of hard 50 sheet material, including horizontal and vertical portions enabling application to the edge of the wagon box at the place of wear, and a portion bent upon itself and away 55 from the aforesaid portions to provide a resilient extra thickness at the place of contact of the wheel.

2. A guard for wagon boxes, comprising a sheet of hard material, bent to form portions at right angles to each other for application to the edge of the wagon box and including a portion extending at an angle, of double thickness at the place of contact of the wheel, said guard including an outwardly bent clamp head with a notch and 60 downwardly bent lugs to receive and retain 65 a portion of an operatively associated clamp rod.

3. A wheel guard for wagon bodies, comprising a substantially square sheet of hard 70 material, bent diagonally and then upon itself to provide a guard portion of double thickness, said sheet then being bent at right angles to the body portion, again at right angles to lie in a plane parallel to the body 75 portion, and then down to provide a pair of lugs, said lugs being formed at the sides of a notch for receiving the end of an operatively associated clamp rod.

4. In a farm wagon, a sheet metal guard, 80 comprising a plate bent diagonally, then upon itself to form a portion of double thickness, and then at right angles to the body portion to enable the application of the guard to the edge of the wagon box, a clamp head included in the vertical portion, with a notch and retaining lug; and a clamp rod applied to the side board of the wagon, including a threaded portion extending into said notch, a wing nut applied to said threaded portion to lock the guard 85 and clamp rod together, and a member introduced into the clamp head to lie in proximity to the wing nut to keep the latter 90 from turning off.

LEVI P. WELLS.
